E. H. Stewart,
Halter Clasp.
No. 90,164. Patented Oct 26, 1869.

United States Patent Office.

E. H. STEWART, OF PHILADELPHIA, PENNSYLVANIA.

Letters Patent No. 96,164, dated October 26, 1869.

IMPROVED HALTER-CLASP.

The Schedule referred to in these Letters Patent and making part of the same.

To all whom it may concern:

Be it known that I, E. H. STEWART, of the city of Philadelphia, in the county of Philadelphia, in the State of Pennsylvania, have invented a new and useful Improvement in "Halter-Clasps," and I do hereby declare that the following is a full and exact description thereof, reference being had to the accompanying drawings, making a part of this specification, in which—

Figure 1 is a perspective view of my invention, clasp and halter combined.

Figure 2 is a side-elevation view of the clasp.

Figure 3 is a top plan view of my clasp.

Figure 4 is an under plan view of my clasp.

Figure 5 is a sectional elevation of the clasp, showing how attached to the halter.

The nature of my invention consists in a certain clasp, made in such a way that it can be attached to a halter without being sewed on, and which can be slipped on the halter forward or backward, will allow the halter to be used around or attached to a post of any size.

To enable others skilled in the art to make and use my invention, I will now proceed and describe its construction and operation.

C C is the body of a cast-metal clasp, of the shape shown in figs. 1, 2, 3, and 4.

H is the front end of the clasp, and is bent as a hook.

The clasp is cast, and made as shown in figs. 5, 4, and 3.

K K' K" being openings in the metal, and D, E, and E', lugs, running from one side to the other.

F is the place designed for the rivets, securing P, the spring, to the clasp.

The thickness of metal F F E must be such that

the under face of E shall be a little lower than the top face of lugs D and E'.

Now, if I insert the halter in opening K, forcing it under lug E, then out through opening K', then in again through opening K", the lug E, being lower than lugs D and E', will bear with friction on the halter, passing under it, and it will be thus necessary to pull with a certain amount of strength, to slip the clasp backward or forward.

As to the halter, it bears, on one of its ends, as usual, a buckle, B, designed to be hooked on hook H, and held there, by means of spring P, in the usual way. (Fig. 1.)

The construction and operation of this clasp are so simple, and plainly shown in figs. 1 and 5, that it needs no further explanation but to say that the mere sliding of the clasp backward or forward will shorten or lengthen the diameter of the loop M, and thereby fit the halter around posts or trees of any reasonable diameter; and again, if the horse thus hitched were to pull very violently, it would have the tendency to tighten the loop, the clasp and loop acting as a noose in such a case.

I am aware that halters are and have been provided with spring-clasps, attached unto them in various ways, but I am not aware that any have ever been attached to halters in the way above described; and, therefore,

What I claim as my invention, and desire to secure by Letters Patent of the United States, is—

A halter-clasp, when constructed and operated in the manner and for the purpose above set forth and described.

E. H. STEWART.
